Ernest L. Du Pree, Weston, Conn., and James Rosati, New York, N. Y., assignors to Schenley Industries, Inc., New York, N. Y., a corporation of Delaware

Application November 8, 1957, Serial No. 48,379

Term of patent 14 years

(Cl. D58—6)

The side of the decanter opposite that shown is the same as that illustrated herein.

We claim:

The ornamental design for a decanter, as shown and described.
